TRAILER WASTE OUTLET COUPLING WITH
REVERSELY THREADED MEMBERS

Claude E. Hand, 1402 3rd St., La Grande, Oreg. 97850

Filed July 28, 1971, Ser. No. 167,092

Term of patent 14 years

Int. Cl. D23—01

U.S. Cl. D23—43

FIG. 1 is a side elevational view of the trailer waste outlet coupling with reversely threaded members showing my new design,

FIG. 2 is a left end elevational view thereof, and FIG. 3 is a right end elevational view thereof.

I claim:

The ornamental design for a trailer waste outlet coupling with reversely threaded members, as shown.
